UNITED STATES PATENT OFFICE.

FREDERICK JOHN EDWIN CHINA, OF ESHER, ENGLAND.

MINUTE DISINTEGRATION OF SUBSTANCES.

Continuation of application Serial No. 599,038, filed November 4, 1922, and in Great Britain March 8, 1922. This application filed December 10, 1923. Serial No. 679,748.

My invention relates to improvements in the minute disintegration of substances, and more particularly to mills for that purpose and is a continuation of my application filed Nov. 4, 1922, Serial No. 599,038.

An object of my invention is to finely divide particles to an extremely small diameter, while at the same time insuring great uniformity of size of particles.

Another object of my invention is to utilize forces existing within a thin film of liquid in which the particles are suspended, such film existing between closely adjacent surfaces relatively movable past each other at high velocity.

A further object of my invention is to provide methods and apparatus for minutely disintegrating particles which accomplish the disintegration of a large amount of substances in a short time, with a minimum consumption of power.

Yet another object of my invention is to provide methods and apparatus for disintegrating particles in which there is a minimum of wear on the machinery, and a minimum amount of heat generated by the working surfaces.

A still further object is to provide apparatus which is simple in operation, cheap to manufacture, and easy to adjust, repair and replace.

With these and other objects in view which may be incident to my improvements, the invention consists in the parts and combinations to be hereinafter set forth and claimed, with the understanding that the several necessary elements comprising my invention, may be varied in construction, proportions and arrangement, without departing from the spirit and scope of the appended claims.

In order to make my invention more clearly understood, I have shown in the accompanying drawings means for carrying the same into practical effect without limiting the improvements in their useful applications to the particular constructions, which for the purpose of explanation, have been made the subject of illustration.

In the drawings:—

Fig. 1 is a longitudinal sectional view.

Fig. 2 is a cross sectional view of the detail of the bearing support taken on the line 2—2 of Fig. 1, looking in the direction of the arrows;

Fig. 3 is a detail view partly in section illustrating a modification of my device in which the input chamber is made very small;

Fig. 4 is a longitudinal sectional view of a modification of my device taken through the axis of the rotor, illustrating a form in which the substances to be disintegrated may be introduced on the film itself;

Fig. 5 is a detail of the stator of the modification shown in Fig. 4, taken on the line 5—5 of Fig. 4, looking in the direction of the arrows;

Fig. 6 shows another modification of rotor and stator which I may use;

Fig. 7 diagrammatically indicates the direction of some of the forces acting on the liquid in my device;

Fig. 8 diagrammatically illustrates the path of the particles in passing between the relatively movable surfaces of my mill.

My invention comprises passing, a thin film of liquid with the suspended particles of liquid or solid therein, between surfaces relatively movable one past the other at high velocity. There are generated in the thin film of liquid thus acted upon forces which act upon the particles, liquid or solid, suspended in the liquid, and where the clearance between the moving surfaces is small enough and the velocity of relative movement of the surfaces is great enough, particles will be disrupted. The relative velocities of the surfaces and their distance apart, as well as the time of the operation and the temperature at which it is carried out, determine the amount of force to which the particles are subjected. Generally speaking, the greater the speed, the greater the disruptive forces, and the more closely adjacent the surfaces, the greater the disruptive forces.

It is necessary that the liquid, with the suspended particles therein, be retarded in its passage between the relatively movable surfaces. Such retarding, however, necessarily takes place by reason of the friction between the liquid and the relatively movable closely adjacent surfaces, so that there is sufficient retarding in forms of my apparatus where the film of liquid passes freely between disks.

Referring to the drawings, and particularly to Figs. 1 to 4 inclusive, I have shown a mill which comprises a base casting 1 adapted to be bolted to a suitable support, by means of a series of bolts 2. The casting 1 is

formed with a lower annular flange 3, and an upper annular flange 4 through which the bolts 2 that hold the device in place pass. Formed within the casting 1 is a fluid containing chamber 5, having an inlet pipe 6 and an outlet pipe 7 leading into the chamber and adapted to discharge at a point near its top. The purpose of the inlet and outlet pipes is to allow either heating or cooling fluid, such as steam or cooling brine, to be circulated in the chamber 5 to either raise or lower the temperature at which the operation takes place, if such regulation is found desirable.

15 Formed within the bottom portion of the casting 1 is an input duct 8, through which the liquid containing the particles to be disintegrated is introduced into the machine. The particles to be disintegrated if they are 20 of great degree of hardness, must be of less diameter than the distance between the working surfaces (later to be described), otherwise said surfaces will be injured or scored.

25 Formed in the upper part of the casting 1 is a smooth frustro-conical working surface 9, and between the working surface 9 and the input duct 8 is comprised a conical input chamber 11.

30 Mounted on the casting 1 is a cover plate 12, which forms with the casting 1 an output chamber 13, from which an output duct 14 leads.

35 The casting 1 is formed with an annular shoulder 16 at its top, and the cover plate 12 is provided with an annular groove 17 in which the shoulder 16 of the casting 1 fits. Between the groove 17 and the shoulder 16 I 40 insert suitable packing material 18.

45 The cover plate 12 is provided with an annular flange 19, which overlies the annular flange 4 of the casting 1; the bolts 2 which hold the casting 1 to the support pass through the flange 19, as well as the flanges 3 and 4 of the casting 1, and hold the cover plate 50 firmly in place. For purposes of carefully adjusting the relative position of the cover plate 12 to the casting 1, I have provided a series of wedges 21, one of which is shown in Fig. 1. The wedges are adapted to lie between the bolts 2, and in practice I have found that three wedges will enable good adjustment to be made. By means of these wedges, a careful adjustment of the relative position of the cover plate 12 to the casting 55 1 may be made, in order to properly center the working parts.

60 Mounted on top of the casting 12 is a supporting structure 22. The supporting structure 22 is provided with a flange 23 at its lower end, which is adapted to lie in contact with the top of the cover plate 12. The inner periphery of the flange 23 of the support piece is adapted to abut against an annular shoulder 24 formed on the cover plate 65 12. A series of holding bolts 25 hold the

support member 22 in position. The support member 22 has, preferably integrally formed therewith, upwardly extending support spiders 26, which terminate at their upper extremity in a ring member 27; the interior surface of the ring member being screw-threaded, as indicated at 28.

A bearing support piece 29 is provided, on its downwardly extending annular portion 31, with screw-threads 32, which are adapted to engage with the screw-threads 28 of the ring member 27, permitting the bearing support 29 to be adjustable. A lock nut 33 is provided to lock the bearing support 29 in any adjusted position, and a pointer 34, attached to the supporting structure 22, is provided to co-operate with a scale on the periphery of the bearing support 29 and indicate the adjustment.

35 My mill is provided with a conical rotor 35 having a smooth frustro-conical working surface 36 adapted to lie adjacent the smooth frustro-conical working surface 9 of the casting 1 and equi-distantly spaced therefrom. The rotor 35 is mounted on a shaft 37 and 40 held securely on the shaft by means of a nut 38. On the upper end of the shaft 37 are screw-threads 39 upon which are adapted to be screwed locking nuts 41. Below the screw-threads 39, the shaft 37 has a slightly enlarged portion 42 over which is adapted to fit an inner upper ball race 43. An outer upper ball race 44 is adapted to fit in a cylindrical aperture 45 formed in the bearing support 29. Between the inner and outer ball races are 45 two series of balls 46.

50 Below the portion 42, the shaft is slightly enlarged, as indicated at 47, and around the upper part of the portion 47 of the shaft is fitted a collar 48, whose upper end contacts with the upper inner ball race 43. The bearing support 29 is provided with a downwardly extending annular shoulder 49, having annular packing glands 51 therein, in which is packed suitable packing to prevent leakage 55 of lubricant from the bearing. A journal box cover 52 is bolted by means of bolts 53 to the bearing support 29. The journal box cover 52 has a downwardly projecting annular lip 54, and the upper outer ball race 44 is firmly held between the annular lip 54 and the shoulder 49 formed on the bearing support member 29.

55 The bearing structure, comprising the inner and outer upper bearing races and the balls, operates as a thrust and radial bearing. The bearing will withstand thrust in either direction. I prefer to use the type commercially known as the "Skefko" bearing, which is made in Sweden, as this type of bearing will stand thrust and at the same time can be operated at exceedingly high speed without overheating or play.

60 On the portion 47 of the shaft 37 is a drive pulley 55, which is keyed to the shaft, and 130

against which the lower end of the collar 48 rests. The cover plate 12 is provided with an annular recess 56, within which is mounted the lower bearing and packing structure, 5 which I will now describe. Mounted on the portion 47 of the shaft extending below the pulley 55 is a collar 57, whose upper end is adapted to engage the lower end of the pulley 55. The collar is mounted within a packing 10 gland comprising a plate 58 which lies over the upper end of the annular recess 56, and is bolted by means of bolts 59 to the upper side of the cover plate 12. The plate 58 is provided with two annular recesses 61 on its inner periphery within which is placed a suitable packing to form a tight packing joint around the collar 57.

Mounted below the collar 57 on an enlarged portion 62 of the shaft 37 is an inner ball race 63, whose lower end rests against the shoulder formed between the portion 62 of the shaft, and an enlarged lower portion of the shaft 64. The upper portion of the inner ball race 63 is in contact with the lower portion of the 25 collar 57. Arranged to slidably fit within the walls of the annular recess 56 is an outer ball race 65.

To prevent leakage of lubricant through the lower opening of the annular recess 56, 30 through which the portion 64 of the shaft 37 passes, I have formed the annular recess 56 with an inwardly projecting annular shoulder 67. Below the shoulder 67, the inner walls of the recess 56 are inwardly tapered 35 at 68 adjacent the point at which the portion 64 of the shaft 37 passes through the lower part of the cover plate 12.

Fitting around the portion 64 of the shaft is a packing plate 69 having a shoulder 71, 40 lying above the shoulder 67 of the cover plate 12, with its outer periphery in engagement with the inner periphery of the annular recess 56. The packing plate 69 is formed with a downwardly extending lip 72, which fits 45 around the portion 64 of the shaft 37. Between the lower edge of the downwardly extending lip 72 and the sloped walls 68 in the cover plate, I have inserted packing material 73 to prevent leakage of lubricant.

To hold the packing plate 69 pressed 50 against the packing 73, I have formed an annular groove 74 in the wall of the recess 56. Within this groove I mount a split ring 75, whose elasticity when sprung into position 55 keeps the packing plate 69 pressing against the packing 73. The packing gland thus formed is adapted to ordinarily withstand a pressure of about twenty-five pounds without leakage. This packing gland near the lower 60 portion of the cover plate, not only serves to prevent lubricant from leaking out of the lower bearing structure, but at the same time provides means for preventing liquid within the output chamber 13 of the mill from passing 65 into the lower bearing, should any con-

siderable pressure be generated in this output chamber.

Adjustment of the clearance between the fixed working surface 9 and the rotating working surface 36 of the rotor 35, can be 70 very easily and accurately effected by loosening the lock nut 33, on the threaded portion 31 of the bearing support 29, and rotating the bearing support 29 until the exact adjustment is obtained. The working surfaces 75 are held equi-distantly and fixedly spaced when the lock nut 33 is screwed in place. The pointer 34 enables the person performing the adjustment to accurately tell the degree of 80 rotation imparted to the bearing support 29. As before stated, the bearing support 29 is 85 preferably formed with a scale on its outer periphery for co-operation with the pointer 34, to enable an accurate adjustment to be obtained.

The whole upper bearing structure is either raised or lowered by rotating the bearing support 29. The outer upper ball race 44 is moved with the bearing support, and through the balls 45, carries the inner ball race 43 with it. The inner ball race is held against longitudinal displacement on the shaft by the collar 49 whose lower end abuts the fixed pulley 55, and by the lock nuts 41. By reason of the fact that the lower inner ball race 63 is held against longitudinal movement on the shaft by the collar 57, and the shoulder formed at the upper extremity of the portion 64 of the shaft, the lower inner ball race 63 must move with the shaft. The balls 66 cause the outer ball race 65 to slide either up or down within the annular recess 56 in accordance with the adjustment of the shaft.

It will be apparent by reason of the bearing mountings and the shaft structure, that when the upper bearing support 29 is either raised or lowered, the lower bearing moves with it.

One of the support spiders 26 is made of 110 less arcuate breadth than the other support spiders to permit a belt to pass readily over the pulley 55. A suitable source of power moves the belt 76, which imparts rotation to the pulley 55 to cause the rotor 35 to rotate. The screw-threads which are formed on the upper bearing support 29 are in such a direction, that the normal direction of rotation of the belt will cause the upper bearing support 29 to unscrew in case the lock nut 33 is not tightly adjusted to prevent such an 115 occurrence. This gives an added factor of safety, for should the proper tightening of the lock nut 33 not be effected, the normal operation of the machine will tend to continually increase the distance between the smooth conical working surfaces, thus preventing injury to the machine.

I have found that in disintegrating particles, liquid or solid, suspended in a liquid, 120

that the clearance between the working surfaces should ordinarily be approximately from two-thousandths of an inch to twenty-thousandths of an inch.

5 The peripheral speed of the rotor may vary from approximately 150 feet a second to 600 feet a second, depending upon the operating conditions.

In operation, the particles to be disintegrated are suspended in a suitable liquid medium, such as water. The particles to be disintegrated may be either liquid or solid particles. While I have given speeds and clearances, as above outlined, it is to be distinctly understood that I am not limited to any exact speeds and clearances which lie within the scope of my invention.

The liquid, with the suspended particles therein, is introduced through the input duct 20 and passes into the input chamber 11. The rotor is moving at a high rate of speed, and the liquid with the suspended particles is sucked in between the working surfaces and ejected into the output chamber. During 25 the brief time that the liquid with the suspended particles takes in passing from the input chamber, through the film and into the output chamber, the particles have been disrupted and will be found to be of much 30 smaller diameter. It has been difficult to investigate exactly what happens within the film and exactly what forces are at work, but certain evidence has been obtained in the following manner:

35 It has been found that in a mill designed according to my invention and having two concentric co-axial and co-acting conical working surfaces, the material dealt with has produced curved or stream-line markings on 40 the concave conical working surface of the stator. It is not clear whether these markings are produced chemically or mechanically. In all probability, a combination of effects has been at work. These markings, 45 however, give an indication of the path of the particles through the mill. On investigating the markings, it has been found that they offer a simple means of deducing the actual velocity of the particles within the film.

50 From the thickness of the film, length of path of the particles as shown by markings on the stator, general dimensions of the mill, rate at which the liquid is passing through the film, and clearance between the working 55 surfaces, the velocity of the particles along their path within the film can be calculated.

Referring to Fig. 8, I have diagrammatically shown the stream-line markings as found on the stator or concave conical working surface of the form of mill shown in Figs. 1 to 3, inclusive.

The mean of a number of experiments shows that this velocity with this form of mill is less than half the peripheral velocity 60 of the rotor. Now the velocity of any par-

ticle within the film depends chiefly on the following factors:—

- (1) Revolution-speed of the rotor.
- (2) Diameter of the rotor.
- (3) Angle of the rotor.
- (4) Thickness of the film.
- (5) Speed of the liquid through the film (the liquid being either pumped or sucked through the film space).
- (6) Viscosity of the liquid.

In Fig. 7, which represents a section through the conical surfaces of a mill comprising a rotor and stator as described in Figs. 1 to 3 inclusive, R is a portion of a rotor which constitutes the inner and moving working surface. The outer and stationary working surface is designated by the letter S.

Liquid enters the film or clearance space between the surfaces R and S in the direction shown by the arrow C. When inside the film, the main forces at work on it are as follows: When the liquid comes in contact with the rotor, the latter imparts to it a velocity in a circumferential direction, and in fact, tends to carry the film around with itself. Centrifugal force, however, is also imparted to the liquid, tending to throw the liquid away from the rotor against the stationary surface in the direction indicated by arrow T. The final component of this force along the direction indicated by the arrow V ejects the liquid from the film confines.

It is thus apparent that the centrifugal force under ordinary circumstances plays an important factor in regulating the time during which the particles are subjected to the disruptive forces existing within the film, as well as the magnitude of such forces. The disruptive forces are believed to be due to the shearing action which occurs within the film. There is no true grinding action which takes place within my mill. This latter fact permits of large output with small utilization of power, and saves wear and tear on the working parts. There is but slight heating of the mill for a long continued operation at high speed, which shows that but little force is dissipated in production of heat.

The operation may be carried on at reduced or elevated temperature by means of introduction of cooling or heating fluid into the chamber 5.

By reason of the fact that the working surfaces are held fixedly spaced, there can be no accidental touching of the working surfaces and hence injury to the mill. The exact thickness of the film for any one operation once determined will not vary during the operation, for any changes in the relative pressures existing between the input chamber and the output chamber cannot affect the adjustment.

In Fig. 3 I have shown a modification of my mill in which the input chamber 11 is

materially reduced in size. Under certain conditions of operation I have found a small input chamber to be advisable. The conical rotor 35 revolving at high speed causes suction in the input chamber 11 by reason of the centrifugal action on the liquid. This action causes the feeding of material through the mill, but where there is a large input chamber, under certain conditions, a partial vacuum may be produced. The material is then fed in pulses, but where the input chamber is restricted in size, there is small danger of pulsation, since a large quantity of the liquid cannot be evacuated from the input chamber at one time. Under certain working conditions, the modification shown in Fig. 3 has been found a preferred form in practice.

In the form of invention illustrated in Figs. 4 and 5, I have shown a type of mill in which the material to be disintegrated may be introduced on the film itself, without mixing it with the liquid which acts as a suspending medium in the input chamber of the mill.

Referring to Figs. 4 and 5, I have shown a mill in which passages 100 and 101 are formed in the base casting 1, such passages communicating at their upper ends with the smooth conical surface 9 of the stator element of the mill. Through suitable pipe connections (not shown) the materials to be disintegrated may be introduced through the passages 100 and 101 directly on the film between the working surfaces, thereby eliminating the mixing of the material to be disintegrated with the liquid in which the suspension is to be made. The passages 100 and 101 are preferably of elongated shape, as shown in Fig. 7, though the particular shape or exact location of the passages vary under different operating conditions.

This type of mill is of particular application in those cases where it is not desirable to mix the constituents before being acted upon by the disruptive forces existing in the film. For instance, suppose I desire to make a finely divided lead chromate suspension in water. If the solution of lead salt is mixed with a solution of a chromate prior to being fed into the mill, then the precipitation of lead chromate so formed will commence to crystallize at once. However, if the solution of the chromate in water is introduced through the input duct 8, and the mill started, so that disruptive forces exist within the film, then the solution of lead salt may be fed in through duct 101 and duct 100. The mixture then takes place on the film in the presence of disruptive forces, with the result that the forces get to work before crystallization takes place, and a very finely divided lead chromate in suspension in water is obtained.

It is, of course, obvious that in all instances it is not necessary to have two ducts for feeding material to be disintegrated on the film,

as in many instances one duct will suffice, while in other cases it may be necessary to have more than two ducts. In those instances where the substances to be mixed in the presence of the disruptive forces are numerous and their admixture prior to subjecting them to the forces of the film is inadvisable, each different material may be fed through a separate duct.

In another modification illustrated in Fig. 6, I have shown a base 252 having a frustoconical working surface 253. In the base is formed a shallow conical depression 254 which operates as an input chamber. Passing through the base 252 is an input duct 255, which leads to the input chamber 254.

Mounted above the base 252 is a rotor 256 suitably attached to a shaft 257. The rotor 256 is provided with a downwardly and obliquely extending flange 258, upon the inner surface of which is formed a working surface 259, which is adapted to lie closely adjacent to the working surface 253 of the stator.

In this type of mill, the working surface 90 which is imparting the centrifugal force, to the particles is the surface against which the particles are tightly pressed by such centrifugal force. In this type of mill the particles are held pressed against the moving surface.

While I have shown and described the preferred embodiment of my invention, I wish it to be understood that I do not confine myself to the precise details of construction 100 herein set forth, by way of illustration, as it is apparent that many changes and variations may be made therein, by those skilled in the art, without departing from the spirit of the invention, or exceeding the scope of the appended claims.

I claim:—

1. An apparatus for disintegrating particles, liquid or solid, suspended in a liquid comprising, closely adjusted adjacent surfaces relatively movable one past the other at high velocity, means for holding the surfaces fixedly spaced, means for causing such movement of said surfaces, and means for introducing the fluid in a film between said surfaces whereby the particles are disintegrated by reason of the disruptive forces within the film.

2. An apparatus for disintegrating particles, liquid or solid, suspended in a liquid comprising, smooth closely adjacent surfaces relatively movable one past the other at high velocity, means for holding the surfaces fixedly spaced, means for causing such movement of said surfaces, and means for introducing the fluid in a film between said surfaces whereby the particles are disintegrated by reason of the disruptive forces within the film.

3. An apparatus for disintegrating par-

6. An apparatus for disintegrating particles, liquid or solid, suspended in a liquid comprising, closely adjacent equidistantly spaced surfaces relatively movable one past the other at high velocity, means for holding the surfaces fixedly spaced, means for causing such movement of said surfaces, and means for introducing the fluid in a film between said surfaces whereby the particles are disintegrated by reason of the disruptive forces within the film. 70
7. An apparatus for disintegrating particles, liquid or solid, suspended in a liquid comprising, smooth closely adjacent equidistantly spaced surfaces relatively movable one past the other at high velocity, means for holding the surfaces fixedly spaced, means for causing such movement of said surfaces, and means for introducing the fluid in a film between said surfaces whereby the particles are disintegrated by reason of the disruptive forces within the film. 75
8. An apparatus for disintegrating particles, liquid or solid, suspended in a liquid comprising, a member having a smooth frusto-conical working surface, a second member having a smooth frusto-conical working surface closely adjacent to and equi-distantly spaced from the first mentioned surface but having no points of contact therewith, means for keeping said working surfaces fixedly spaced, means for causing one member to rotate with respect to the other, and means for introducing the liquid in a film between said working surfaces, whereby the particles are disintegrated by reason of the disruptive forces within the film and ejected by the centrifugal forces acting on the film. 80
9. An apparatus for disintegrating particles, liquid or solid, suspended in a liquid comprising, a fixed member having a smooth frusto-conical working surface, a rotatable member having a smooth frusto-conical working surface closely adjacent to the first mentioned surface, means for holding the surfaces fixedly spaced, means for causing one member to rotate with respect to the other, and means for introducing the liquid in a film between said working surfaces whereby the particles are disintegrated by reason of the disruptive forces within the film and ejected by the centrifugal forces acting on the film. 85
10. An apparatus for disintegrating particles, liquid or solid, suspended in a liquid comprising, a fixed member having a smooth frusto-conical working surface, a rotatable member having a smooth frusto-conical working surface closely adjacent to and equi-distantly spaced from the first mentioned surface but having no points of contact therewith, means for keeping said working surfaces fixedly spaced, means for causing the rotatable member to rotate with respect to the fixed member, and means for introducing the liquid relatively near the axis of rotation of the rotating member, whereby the particles are disintegrated by reason of the disruptive forces within the film, and are discharged by centrifugal force at a position more remote from the axis of rotation of the rotatable member than the place of introduction of said particles. 90
11. An apparatus for disintegrating particles, liquid or solid, suspended in a liquid comprising, a fixed member having a smooth frusto-conical working surface, a rotatable member having a smooth frusto-conical working surface closely adjacent to the first mentioned surface but having no points of contact therewith, a shaft on which the rotatable member is mounted, means co-operating with the shaft for taking thrust in both directions to keep the working surfaces fixedly spaced, means for rotating the shaft, and means for introducing liquid in a film between said working surfaces, whereby the particles are disintegrated by reason of the disruptive forces within the film and ejected by the centrifugal forces acting on the film. 95
12. An apparatus for disintegrating particles, liquid or solid, suspended in a liquid comprising, a fixed member having a smooth working surface, a rotatable member having a smooth working surface closely adjacent to the first mentioned surface but having no points of contact therewith, a shaft on which 100

- the rotatable member is mounted, means cooperating with the shaft for taking thrust in both directions to keep the working surfaces fixedly spaced, means for rotating the shaft at high velocity, and means for introducing the liquid in a film between said working surfaces whereby the particles are disintegrated by reason of the disruptive forces within the film.
- 10 12. An apparatus for disintegrating particles, liquid or solid, suspended in a liquid comprising, a fixed member having a smooth working surface, a rotatable member having a smooth working surface closely adjacent to the first mentioned surface but having no points of contact therewith, a shaft on which the rotatable member is mounted, a bearing moving with the shaft and capable of taking thrust in both directions to keep the working surfaces fixedly spaced a desired distance, means for adjusting the position of the bearing to regulate the separation of the working surfaces, means for rotating the shaft at high velocity, and means for introducing the liquid in a film between said working surfaces, whereby the particles are disintegrated by reason of the disruptive forces within the film.
13. An apparatus for disintegrating particles, liquid or solid, suspended in a liquid comprising, a fixed member having a smooth working surface, a rotatable member having a smooth working surface closely adjacent to the first mentioned surface but having no points of contact therewith, a shaft on which the rotatable member is mounted, a support, a bearing carried by the support and moving with the shaft, and capable of taking thrust in both directions to keep the working surfaces fixedly spaced a desired distance, an adjusting member having screw-threaded engagement with the support for moving the bearing, means for rotating the shaft at high velocity and means for introducing the liquid in a film between said working surfaces, whereby the particles are disintegrated by reason of the disruptive forces within the film.
14. An apparatus for disintegrating particles, liquid or solid, suspended in a liquid comprising, a fixed member having a smooth working surface, a rotatable member having a smooth working surface closely adjacent to the first mentioned surface but having no points of contact therewith, a shaft on which the rotatable member is mounted, a support, an adjusting member having screw-threaded engagement with the support, a bearing moving with the shaft, housed in the adjusting member and capable of taking thrust in both directions to keep the working surfaces fixedly spaced a desired distance, means for rotating the shaft, and means for introducing the liquid in a film between said working surfaces, whereby the particles are disintegrated by reason of the disruptive forces within the film.
15. An apparatus for disintegrating particles, liquid or solid, suspended in a liquid, comprising a fixed member having a smooth working surface, a rotatable member having a smooth working surface closely adjacent to the first mentioned surface but having no points of contact therewith, a shaft on which the rotatable member is mounted, a support, an adjusting member having screw-threaded engagement with the support, a bearing moving with the shaft, housed in the adjusting member and capable of taking thrust in both directions to keep the working surfaces fixedly spaced a desired distance, a lock nut mounted on the adjusting member and cooperating with the support to prevent change of adjustment during operation, means for rotating the shaft, and means for introducing the liquid in a film between said working surfaces, whereby the particles are disintegrated by reason of the disruptive forces within the film.
16. An apparatus for disintegrating particles, liquid or solid, suspended in a liquid comprising, a fixed member having a smooth working surface, a rotatable member having a smooth working surface closely adjacent to the first mentioned surface but having no points of contact therewith, a shaft on which the rotatable member is mounted, a support, a bearing carried by the support and moving with the shaft, and capable of taking thrust in both directions to keep the working surfaces fixedly spaced a desired distance, an adjusting member having screw-threaded engagement with the support for moving the bearing, a second bearing support, a ball bearing mechanism adapted to slide in said second bearing support, means for rotating the shaft, and means for introducing the liquid in a film between said working surfaces, whereby the particles are disintegrated by reason of the disruptive forces within the film.
17. An apparatus for disintegrating particles, liquid or solid, suspended in a liquid comprising, closely adjusted surfaces relatively movable one past the other at high velocity, means for holding the surfaces fixedly spaced, means for causing such movement of said surfaces, an input chamber, an output chamber, a fluid jacket adjacent the input chamber having an inlet and an outlet whereby the temperature of the operation may be regulated, and means for introducing the fluid in a film between said surfaces, whereby the particles are disintegrated by reason of the disruptive forces within the film.
18. An apparatus for disintegrating particles, liquid or solid, suspended in a liquid comprising, smooth closely adjacent equidistantly spaced surfaces relatively movable

one past the other at high velocity, means for holding the surfaces fixedly spaced, means for causing such movement of said surfaces, an input chamber, an output chamber, a fluid jacket adjacent the input chamber having an inlet and an outlet whereby the temperature of the operation may be regulated, and means for introducing the fluid in a film between said surfaces whereby the particles are disintegrated by reason of the disruptive forces within the film.

19. An apparatus for disintegrating particles, liquid or solid, suspended in a liquid comprising, a fixed member having a smooth frustro-conical working surface, a rotatable member having a smooth frustro-conical working surface closely adjacent to and equi-distantly spaced from the first mentioned surface, means for holding the surfaces fixedly spaced, means for causing the rotatable member to rotate with respect to the fixed member, an input chamber, an output chamber, a fluid jacket adjacent the input chamber having an inlet and outlet whereby the temperature of the operation may be regulated, and means for introducing the liquid relatively near the axis of rotation of the rotatable member, whereby the particles are disintegrated by reason of the disruptive forces within the film and are discharged by centrifugal force at a position more remote from the axis of rotation of the rotatable member than the place of introduction of said particles.

35 20. An apparatus for disintegrating particles, liquid or solid, suspended in a liquid comprising, a member having a smooth frustro-conical working surface, a second member having a smooth frustro-conical working surface closely adjacent to and equi-distantly spaced from the first mentioned surface but having no points of contact therewith, means for keeping said working surfaces fixedly spaced, an input chamber, a fluid jacket adjacent the input chamber having an inlet and an outlet, and means for causing one member to rotate with respect to the other member, whereby the particles are disintegrated by reason of the disruptive forces within the film and ejected therefrom by reason of the centrifugal forces acting on the film.

21. An apparatus for disintegrating particles, liquid or solid, suspended in a liquid comprising, a fixed member having a smooth working surface, a rotatable member having a smooth working surface closely adjacent to the first mentioned surface but having no points of contact therewith, an input chamber, a fluid jacket adjacent the input chamber having an inlet and an outlet, whereby the temperature of the operation may be regulated, a shaft on which the rotatable member is mounted, a support, a bearing carried by the support and moving with the shaft,

and capable of taking thrust in both directions to keep the working surfaces fixedly spaced a desired distance, an adjusting member having screw-threaded engagement with the support for moving the bearing, means for rotating the shaft at high velocity, and means for introducing the liquid in a film between said surfaces, whereby the particles are disintegrated by reason of the disruptive forces within the film.

70 22. A film mill for the disintegration of particles suspended in a liquid comprising, members having closely adjacent fixedly spaced working surfaces, means for causing said surfaces to move relative to each other at high velocity, and an input chamber of small cubic content whereby the feeding of the liquid in pulses is minimized.

75 23. An apparatus for disintegrating particles, liquid or solid, suspended in a liquid comprising, members having closely adjacent smooth working surfaces, means for keeping said working surfaces fixedly spaced, means for causing said surfaces to move one past the other at high velocity, an input chamber of small cubic content, whereby the feeding of the liquid in pulses is minimized, and means for introducing the liquid in a film between said working surfaces, whereby the particles are disintegrated by reason of the disruptive forces within the film.

80 24. An apparatus for disintegrating particles, liquid or solid, suspended in a liquid, comprising a fixed member having a smooth working surface, a rotatable member having a smooth working surface closely adjacent to the first mentioned surface but having no points of contact therewith, a shaft on which the rotatable member is mounted, means co-operating with the shaft for taking thrust in both directions to keep the working surfaces fixedly spaced, means for rotating the shaft, an input chamber of small cubic content, whereby the feeding of the liquid in pulses is minimized, and means for introducing the liquid in a film between said working surfaces, whereby the particles are disintegrated by reason of the disruptive forces within the film.

85 25. An apparatus for disintegrating particles, liquid or solid, suspended in a liquid comprising, a fixed member having a smooth working surface, a rotatable member having a smooth working surface closely adjacent to the first mentioned surface but having no points of contact therewith, a shaft on which the rotatable member is mounted, a bearing moving with the shaft and capable of taking thrust in both directions to keep the working surfaces fixedly spaced a desired distance, means for adjusting the position of the bearing to regulate the separation of the working surfaces, means for rotating the shaft, and an input chamber of small cubic content, whereby the feeding of the liquid in pulses is

minimized, and means for introducing the liquid in a film to said working surfaces, whereby the particles are disintegrated by reason of the disruptive forces within the 5 film.

26. A method of disintegrating particles suspended in a liquid comprising, subjecting a very thin film of the liquid to the action of closely adjacent non-contacting fixedly 10 spaced surfaces relatively movable one past the other at high velocity, and introducing the particles to be disintegrated on the film itself.

27. A method of disintegrating particles suspended in a liquid comprising, subjecting a very thin film of the liquid to the action of closely adjacent non-contacting fixedly 15 spaced smooth surfaces relatively movable one past the other at high velocity, and introducing the particles to be disintegrated on the film itself.

28. A method of disintegrating particles suspended in a liquid comprising, subjecting a very thin film of the liquid to the action 20 of closely adjacent non-contacting fixedly spaced surfaces relatively movable one past the other at high velocity, the diameter of the particles being less than the distance between the surfaces, and introducing the particles to be disintegrated on the film itself.

29. A method of disintegrating particles comprising, subjecting a very thin film of the liquid to the action of closely adjacent non-contacting fixedly spaced surfaces relatively 25 movable one past the other at high velocity, and introducing a plurality of substances to be mixed and disintegrated at a plurality of different points on the film.

30. An apparatus for disintegrating particles, liquid or solid, suspended in a liquid comprising, a member having a smooth working surface, a second member having a smooth working surface closely adjacent to and equi-distantly and fixedly spaced from the first 40 mentioned surface, and having a duct opening on the smooth working surface, means for causing one member to rotate at high velocity with respect to the other member, means for introducing the liquid in a film between the 45 surfaces, and means for introducing the substances to be disintegrated through said duct.

31. An apparatus for disintegrating particles, liquid or solid, comprising, a member having a smooth working surface, a second 50 member having a smooth working surface closely adjacent to and equi-distantly and fixedly spaced from the first mentioned surface, a plurality of ducts leading from said member to the working surface, means for causing one member to rotate at high velocity with respect to the other, means for introducing the liquid in a thin film between the 55 working surfaces, and means for introducing substances to be mixed and disintegrated 60 through said ducts.

32. An apparatus for disintegrating particles, liquid or solid, suspended in a liquid comprising, a fixed member having a smooth frustro-conical working surface, a rotatable member having a smooth frustro-conical 70 working surface closely adjacent to the first mentioned surface and enclosing the same, a shaft upon which the rotatable member is mounted, means co-operating with the shaft to take thrust in both directions to keep the 75 working surfaces fixedly spaced, and means for rotating the shaft.

33. An apparatus for disintegrating particles, liquid or solid, suspended in a liquid comprising, a fixed member having a smooth frustro-conical working surface, a rotatable member having a smooth frustro-conical 80 working surface closely adjacent to the first mentioned surface and enclosing said first mentioned surface, a shaft upon which the 85 rotatable member is mounted, means co-operating with the shaft to take thrust in both directions to keep the working surfaces fixedly spaced, means for rotating the shaft, and means for introducing liquid in a film 90 between said working surfaces, whereby the particles are disintegrated by reason of the disruptive forces within the film.

34. An apparatus for disintegrating particles, liquid or solid, suspended in a liquid comprising, a fixed member having a smooth frustro-conical working surface, a rotatable member having a smooth frustro-conical 95 working surface closely adjacent to and enclosing said first mentioned surface, a shaft 100 upon which the rotatable member is mounted, means co-operating with the shaft for taking thrust in both directions to keep the working surfaces fixedly spaced, means for rotating the shaft, and means for introducing liquid 105 in a film between said working surfaces, whereby the particles are disintegrated by reason of the disruptive forces within the film.

35. An apparatus for disintegrating particles, liquid or solid, suspended in a liquid comprising, a fixed working surface, a rotor having a smooth working surface adjacent the fixed surface, a shaft for the rotor, a ball race carried by the shaft, a cooperating ball race 110 adjacent the first mentioned race and enclosing it, balls in the races, said races being so constructed that they form with the balls a bearing capable of taking thrust in both directions, and means for adjusting the position of the first mentioned race to effect the longitudinal position of the shaft.

36. An apparatus for disintegrating particles, liquid or solid, suspended in a liquid comprising a fixed working surface, a support, a bearing support member in screw-threaded engagement with the support, a rotor having a smooth working surface adjacent the fixed surface, a shaft for the rotor, and a bearing for the shaft mounted in the 125 130

bearing support member preventing movement of the shaft on its longitudinal axis relative to said bearing and mounted in the bearing support.

- 5 37. An apparatus for disintegrating particles, liquid or solid suspended in a liquid comprising a fixed working surface, a rotor having a smooth working surface adjacent the fixed surface, a shaft therefor, a bearing 10 for the shaft mounted in the bearing support member preventing movement thereof on its longitudinal axis relative to said bearing, a bearing support, and a cover for the bearing support engaging said bearing to cause the bearing to travel with the bearing support.
- 15 38. An apparatus for disintegrating particles, liquid or solid, suspended in a liquid comprising, a fixed working surface, a support, a pointer carried by the support, a bearing support member in screw-threaded engagement with the support, a micrometer head carried by the bearing support member, a rotor having a smooth working surface adjacent the fixed working surface, a shaft for 20 the rotor, and a bearing for the shaft preventing movement of the shaft on its longitudinal axis relative to said bearing and mounted in the bearing support.
- 25 39. An apparatus for disintegrating particles, liquid or solid, suspended in a liquid comprising, a fixed working surface, a support, a bearing support member in screw-threaded engagement with the support, a micrometer head carried by the bearing support member, a rotor having a smooth working surface adjacent the fixed working surface, a shaft for 30 the rotor, a bearing for the shaft preventing movement of the shaft on its longitudinal axis relative to said bearing and mounted in the bearing support.
- 35 40. An apparatus for disintegrating particles, liquid or solid, suspended in a liquid comprising, a fixed working surface, a support, a bearing support member in screw-threaded engagement with the support, a rotor having a smooth working surface adjacent the fixed surface, a shaft for the rotor, a bearing for the shaft preventing movement of the shaft on its longitudinal axis relative to said bearing and mounted in the bearing support, and a cover for the bearing support 35 engaging with said bearing to cause the bearing to travel with the bearing support.
- 40 41. An apparatus for disintegrating particles, liquid or solid, suspended in a liquid comprising, a fixed working surface, a support, a pointer carried by the support, a bearing support, a micrometer head carried by the bearing support, a rotor having a working surface adjacent the fixed working surface, a shaft for the rotor, a bearing for the shaft preventing movement of the shaft on its longitudinal axis relative to said bearing, and mounted in the bearing support, a cover for the bearing support engaging with said bearing to cause the bearing to travel with the bearing support, a member having a recess therein, and a second bearing for the shaft slidably fitting within the recess in said member.

45 42. An apparatus for disintegrating particles, liquid or solid, suspended in a liquid comprising, a fixed working surface, a support, a pointer carried by the support, a bearing support member in screw-threaded engagement with the support, a micrometer head carried by the bearing support member, a rotor having a working surface adjacent the fixed surface, a shaft for the rotor, a bearing for the shaft preventing movement of the shaft on its longitudinal axis relative to said bearing and mounted in the bearing support, and a cover for the bearing support engaging with said bearing to cause the bearing to travel with the bearing support.

50 43. An apparatus for disintegrating particles, liquid or solid, suspended in a liquid comprising, a fixed working surface, a support, a pointer carried by the support, a bearing support, a micrometer head carried by the bearing support, a rotor having a working surface adjacent the fixed working surface, a shaft for the rotor, a bearing for the shaft preventing movement of the shaft on its longitudinal axis relative to said bearing, and mounted in the bearing support, a cover for the bearing support engaging with said bearing to cause the bearing to travel with the bearing support, a member having a recess therein, and a second bearing for the shaft slidably fitting within the recess in said member.

55 44. An apparatus for disintegrating particles, liquid or solid, suspended in a liquid comprising, smooth closely adjacent surfaces relatively movable one past the other at high velocity, means for adjustably holding the surfaces fixedly spaced, means for causing such movement of said surfaces, and means for introducing the fluid in a film between said surfaces, whereby the particles are disintegrated by reason of the disruptive forces within the film.

In testimony whereof I affix my signature.
FREDERICK JOHN EDWIN CHINA.
